[57] CLAIM

The ornamental design for a dolly track switch, as shown and described.

DESCRIPTION

FIG. 1 is a top perspective view showing our track switch design in which tracks to be coupled to the track switch are shown in shadow line;

FIG. 2 is a top plan view thereof;

FIG. 3 is a side elevation view thereof, the opposite side being a mirror image thereof, and the side 90 degrees from the view shown in FIG. 3 being substantially identical excepting that the track portion at the top center is rotated 90 degrees; and,

FIG. 4 is a bottom plan view thereof.
